UNITED STATES PATENT OFFICE.

PERRY BROWN, OF WILMINGTON, DELAWARE.

JOURNAL-BOX.

1,071,872.

Specification of Letters Patent.

Patented Sept. 2, 1913.

Application filed April 27, 1904. Serial No. 205,267.

To all whom it may concern:

Be it known that I, PERRY BROWN, a citizen of the United States of America, and resident of Wilmington, in the county 5 of Newcastle and State of Delaware, have invented certain new and useful Improvements in Journal-Boxes, of which the following is a specification.

This invention relates to certain new and 10 useful improvements in journal boxes for railroad cars and more particularly to an end-closure for the same, and its object is to provide an end-closure of such construction that a portion may be removed when 15 worn and easily replaced by another.

In its preferable embodiment my invention consists of an end-closure which is slid- 20 ingly secured in a groove formed in the end of the box proper and such embodiment is shewn in the accompanying drawings, more particularly hereinafter described and then definitely claimed at the end hereof.

In the said accompanying drawings, which, as I have stated, represent the preferable embodiment of my invention: Figure 1 is a longitudinal central section of a journal box with my improvement thereon. Fig. 2 is a horizontal section through the upper portion of the end-closure. Fig. 3 25 is a perspective view of a portion of the box detached. Fig. 4 is a perspective view of the rear end of the box and the two parts forming the end-closure, said parts being shown in such position as will indicate their 30 mode of detachment. Fig. 5 is an elevation of the parts of the end-closure, detached.

Referring now to the details of the drawings by numerals: 1 designates the box proper which may be of the ordinary or any approved type and which is of course provided with a "lid" 2. As shown in Fig. 1, the journal 3 passes into the box in the usual manner, and the ordinary form of 40 "brass" 4 and "wedge" 5 are also shown in their accustomed positions. The principal difference between the box shown and those in ordinary use is that the rear end of the box is formed in the peculiar way 45 shown in Fig. 4. As there illustrated, it is provided with an opening 6 of any suitable size through which the journal 3 protrudes, and the metal forming the end of the box is formed into a wall 7 thus producing a 50 deep groove 7^a which is preferably open at its upper end. The upper part 8 of the

rear end of the box also projects above the box proper, or, to express it in another way, there is a transverse groove 9 formed in front of this projecting part 8. The opening 6 at the rear end of the box is preferably made much larger, vertically, than the journal 3, so as to permit the box to adjust itself as the brass 4 wears; and as has been hereinbefore mentioned, it is the principal object of my present invention to make a tight fit where the journal passes through this opening. This I accomplish by forming an end-closure which is inserted within the aforesaid groove 7^a, and which may be 60 provided with means to perfectly fit the journal. I do not limit my invention to a device in which this end-closure itself tightly fits the journal, for as will be seen I use a special piece which coacts with and is carried by the end-closure, in order to make a more perfect fit. As seen in Fig. 4, the first of these two parts (the end-closure) is 65 designated by the numeral 10, and is preferably cast with a deep groove around its 70 two sides and its bottom, so that as the end-closure is inserted within the end of the box proper, one wall 12 of the groove on the end-closure 10 passes inside of the groove 7^a, and the other wall 13 passes on the outside of the wall 7, forming the groove 7^a, thus forming a joint which will almost, if 75 not entirely, prevent the oil from oozing out of the end of the box, and the sand and grit from entering therein. In its preferred 80 embodiment, this end-closure 10 is formed with an opening of the peculiar shape 85 shown in Fig. 4. In other words, there is a projecting annular rim or ring 16 forming an opening larger in diameter than the 90 journal, but within this rim or ring is formed a semi-circular portion 17. This 95 makes an opening of rather elongated shape and permits the box to lower itself as the "brass" 4 wears away. This rim or ring 100 is preferably provided with a recess 18 at the top as shown, to receive a lug 27 to be hereinafter described. The upper end of the end-closure is provided with a hood 19 which is provided with an overhanging 105 ledge 20 forming a groove 21 (shown in dotted lines in Fig. 5), this groove being so formed as to fit entirely around the upper part of the aforesaid end 8 and the wall 7, as seen in Fig. 2. It will thus be seen that 110 the hood 19 is so formed as to entirely cover the upper end 8 of the box and thus pre-

vent any dust or grit from entering therein. I deem this a most important feature.

The elongated opening which has been described as being formed in the end-closure 5 sure is, in effect, made the same shape as the journal by having inserted within it a wear-plate of the shape shown in perspective in Fig. 4 and in side elevation in Fig. 5. As there shown it consists of a ring shaped casting 22 provided with a wearing flange 24 which is so located and constructed as to form a continuation of the semi-circular portion 17 hereinbefore described as being formed in the interior of the end-closure 10. These parts, the end-closure 10 and the wear plate 22 thus form a closure for the journal, and said parts together form an opening of the same diameter as the diameter of the journal. This wear plate 22 15 may be secured by any desired means to the end-closure, but I prefer to form ears or lugs 27 and 28, by which the plate 22 is secured to the end-closure by rivets 29.

I desire to call especial attention to the 25 fact that by forming the end-closure with a separate wearing part as 22-24, I am enabled to furnish a journal box which will be exceedingly durable, for the reason that when said part becomes worn, it may be 30 easily removed and a new one inserted in its place. I do not, however, limit my invention to an end-closure having the separate ring, as said part may be formed integral with the end-closure proper. But 35 the advantages of having the ring separate are so great that I much prefer the form shown. It will be noticed, too, that the ring prevents wear on the end of the box, as the collar on the wheel wears against the 40 ring instead of against the box, as would be the case when the journal passes directly into the rear end of the box.

In Fig. 3, and incidentally in Fig. 1, I have shown means for preventing the packing 45 or waste from being fed between the journal and the rear wall of the box, and this coacting with my improved end-closure, forms a box which effectually prevents the escape of the lubricant and the entrance of 50 grit, the latter naturally coming in where the former goes out. This means consists of a semi-circular plate 31 situated immediately under the journal 3 and slightly forward of the end-closure, and it is provided 55 with feet or lateral projections 32 and 33 to support it in position. The upper end of the plate has lugs 34 coacting with lugs 35 cast on the end wall of the box, and the plate is also provided with openings 36 60 through which any lubricant which happens to pass over the top of the plate may pass back into the box proper.

What I claim as new is:

1. A journal box having a grooved end 65 open at the top side, in combination with

an end closure slidably fitted within said grooved end and having an opening therein for the passage of the journal, and a hood formed integrally on the top of said end closure and having a grooved recess therein, 70 and said open upper end of the journal box fitting within the walls forming the grooved recess of said hood and the walls forming said groove inclosing said open upper end on all sides of the same, substantially as 75 described.

2. The combination with a journal box of an end-closure secured thereto and having an opening therein for the journal, and a wearing plate secured to said end-closure 80 and also having an opening for the journal, said end-closure and said wearing plate each surrounding the journal and having complementary portions forming an opening for the journal, substantially as described. 85

3. The combination with a journal box having a grooved rear end, of an end-closure 90 slidably fitted within said grooved end and having an opening for the journal, and a wearing plate secured to said end-closure and also having an opening for the journal; said end-closure and said wearing plate each surrounding the journal and having complementary portions forming an opening for the journal, substantially as 95 described.

4. The combination with a journal box having a grooved rear end, of an end-closure 100 slidably fitted within said grooved end and having an opening for the journal, and a wearing plate secured to said end-closure and also having an opening for the journal; said end-closure and said wearing plate each surrounding the journal and having complementary portions forming an opening 105 for the journal and said end-closure having a hood protecting the upper part of the grooved end of the box, substantially as described.

5. The combination with a journal box 110 having a grooved end, of an end-closure for the same slidably fitted within said grooved end and also formed with a groove into which one wall of the grooved end of the box fits, said end-closure also having 115 an integral hood fitting over the upper end of said grooved end, substantially as described.

6. The combination with a journal box having a grooved end, of an end-closure for 120 the same slidably fitted within said grooved end and also formed with a groove into which one wall of the grooved end of the box fits, said end-closure also having an integral grooved hood fitting over the upper 125 end of said grooved end, substantially as described.

7. The combination with a journal box having a grooved end of an end-closure for the same slidably fitted within said grooved 130

end and also formed with a groove into which one wall of the grooved end of the box fits and a wearing plate secured to said end-closure; said wearing-plate and said 5 end-closure having complementary portions forming an opening for the journal, substantially as described.

Signed by me at Washington, District of Columbia this 19th day of April 1904.

PERRY BROWN.
